Primary Examiner — Michael A. Pratt*(74) Attorney, Agent, or Firm* — Schwabe Williamson & Wyatt, P.C.(57) **CLAIM**

The ornamental design for a magaziner release lever, as shown and described.

DESCRIPTION

FIG. 1 is a side view of a firearm receiver with a magazine release lever.

FIG. 2 is an enlarged view of the magazine release lever of FIG. 1 shown in isolation from the firearm receiver; and, FIG. 3 is a perspective view of the magazine release lever shown in FIG. 2.

The broken lines showing a lower receiver in FIG. 1 illustrate environment which forms no part of the claimed design. Additional broken lines shown in FIGS. 1, 2, and 3 illustrate portions of the magazine release lever that form no part of the claimed design.

1 Claim, 3 Drawing Sheets(56)
